Primary Examiner — Brett Miller*Assistant Examiner* — Jessica M Gebhart*(74) Attorney, Agent, or Firm* — JCIP Global Inc.(57) **CLAIM**

The ornamental design for a toolbox, as shown and described.

DESCRIPTION

FIG. 1 is a perspective view of a toolbox showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and,

FIG. 8 is a perspective view thereof with the handle rotated. The broken lines illustrate portions of the toolbox that form no part of the claimed design.
